FOLDING STRETCHER
 John Conrad Shump, 9920 SW. Terwilliger Blvd.,
 Portland, Oreg.
 Filed Aug. 13, 1963, Ser. No. 301,806
 6 Claims. (Cl. 5—82)

This invention relates to folding stretchers of the class useful to first aid personnel, military personnel, hunters and forest fire fighters.

It is the general object of the present invention to provide a stretcher which may be transported easily in folded position and thereafter opened out readily to a sturdy use position.

It is another object of the present invention to provide a foldable stretcher which can be carried comfortably without binding of chafing.

Still a further object of the present invention is the provision of a foldable stretcher having the webbing releasably mounted for renewal or cleaning.

Still another object of the present invention is the provision of a foldable stretcher the webbing of which provides, when the stretcher is in folded position, a pack cavity of substantial size adapted to receive blankets, supplies, clothing, or other gear.

Yet a further object of the present invention is the provision of a foldable stretcher which is readily manufactured and assembled.

The manner in which the foregoing and other objects of this invention are accomplished will be apparent from the accompanying specification and claims considered together with the drawings, wherein:

FIG. 1 is a plan view of the presently described stretcher opened out to its unfolded use position;

FIG. 2 is a side elevation of the stretcher of FIG. 1 in its unfolded position, illustrating the manner in which it may be folded;

FIG. 3 is a view in side elevation of the presently described stretcher in its folded arrangement;

FIGS. 4 and 5 are transverse sectional views taken along lines 4—4 and 5—5 of FIG. 2, respectively, and illustrating the cross bracing arrangement employed in the herein described folded stretcher; and

FIG. 6 is a detail fragmentary view in elevation of a bracing member taken along line 6—6 of FIG. 5.

In the form of the invention illustrated in the drawings, the folding stretcher of my invention includes a pair of laterally spaced, parallel side rails, each comprised of a plurality of opposed pair of sheet metal sections arranged end to end, hinged together in foldable relation, and supporting stretcher web means. The sections of which the illustrated stretcher is comprised thus include head section 10, central sections 12, 14 and foot section 16.

Head section 10 is defined by side rail sections 18, the upper side margins of which are bent inwardly to form flanges 20. The end edges of the rail sections are beveled to eliminate sharp corners. The flanges 20 of the rail sections contain spaced openings by means of which the stretcher webbing is mounted. Also, their end margins are cut away, as indicated at 22, to provide room for the fastening means used to mount the webbing.

Stretcher section 12 is defined similarly by a pair of rail sections 24 formed with inwardly directed flanges 26 which are perforated to provide webbing mounting openings, and the ends of which are cut away at 28.

Stretcher section 14 is closely similar to section 12, being defined by side rail sections 30, with flanges 32 having perforations and cut away portions 34, as described above.

Foot section 16 in like manner is formed from a pair

2

of parallel rail sections 36 having inwardly directed flanges 38 and web-mounting openings through the flanges.

All of the rail sections thus described conveniently and inexpensively may be stamped from sheet metal of appropriate gauge, which then is bent to form the inwardly-directed, flanged, upper side margins. Preferably, the flanges are bent at an angle of about 45° to the horizontal, as is shown particularly in FIGS. 4 and 5, in order to locate them in a plane which is substantially parallel to the plane of the adjacent webbing, eliminating projecting sharp edges.

Rail sections 18, 24, 30 and 36 are of progressively narrower widths. Accordingly, when their ends are overlapped to form the completed rails, their lower margins lie in substantial alignment to form a continuous, straight, lower edge, as seen in FIG. 2.

The various rail sections are spaced, braced and hinged by cross bar assemblies located at spaced intervals the length of the rails.

Thus there are provided a head cross bar 40, welded or otherwise fixed between side rail sections 18, and a foot cross bar 42 similarly welded or otherwise fixed between foot rail sections 36.

At the joint between rails sections 18 and 24, there is provided a hinging cross bar assembly, illustrated particularly in FIG. 4.

This assembly comprises a U-shaped cross bar 44 of sufficient depth to accommodate, for example, the body of a man lying on the stretcher. The ends of the cross bar are threaded to receive bolts 46. The latter penetrate registering openings through the overlapped ends of rail sections 18, 24 and are threaded into the ends of cross bars 44. In this manner, the cross bar is mounted between the rail sections while at the same time providing a hinge for connecting them.

A similar U-shaped cross bar is provided at the joint between the overlapped ends of rail sections 26 and 30. In this instance the cross bar, indicated at 48, is retained in place by bolts 50.

The cross bar assembly joining the overlapped segments of rails 30, 36 is of somewhat different construction. It is illustrated particularly in FIG. 5.

As shown, it comprises a U-shaped assembly, indicated generally at 52, and including a horizontal cross bar 54 to the ends of which are fixed a pair of vertical plates 56. Angled braces 58, running between the plate and cross bar, stiffen the assembly against both vertical and horizontal stresses. Bolts 60 are received in aligned openings through side rails 30, 36 and plates 52. These secure the cross bar assembly to the side plates, while at the same time hinging the side plates together in foldable relation.

The frame composed of the side rail segments and cross bars mounts webbing means suitable for stretcher use. Preferably the webbing means is supplied in sections 62, 64, 66, 68. Each section is dimensioned to conform to the area of the corresponding stretcher section.

The webbing is mounted on the frame by suitable means, for example, by means of S-hooks 70 mounted in grommeted openings in the webbing, and companion openings in the side rail section flanges, above described.

Appropriate handle means are provided at each end of the stretcher.

To this end side rail sections 18 at the stretcher head have cut away hand openings 72 near their outer ends.

Handles 74 are fixed to the outside face surfaces of the rail sections, convenient to the hand holes, thereby furnishing suitable means for grasping the stretcher head.

Similarly, foot terminal side rail sections 36 are provided with cut out hand openings 76 adjacent their outer ends. Cooperating handles 78 are mounted on the inside face surfaces of the rail sections, thereby providing suitable handle means at the foot end of the stretcher.

It is to be noted that handle members 74 and 78 are mounted on opposite face surfaces of their respective side rail sections so that they will not interfere with each other when the stretcher is folded.

To render the stretcher readily portable when folded, there also are provided a pair of shoulder straps 80. These may be fastened to the stretcher in any suitable manner, preferably stitched to the underside of webbing member 64 in central section 12 of the stretcher.

A cross strap 82 also may be provided. Its purpose is to strap a patient or load on the stretcher during use. Additional cross-straps may be applied when and if necessary.

In use, the stretcher may be used in the unfolded position of FIGS. 1 and 2, in which segments of flanges 20, 26, 32, 38 which overlie the adjacent segments of the flanges of the nesting side rail sections maintain the stretcher rigidly in its straight line, operative position, where it is braced and additionally strengthened by cross bars 40, 42, 44, 48, 52.

When the stretcher is not in use, it may be folded by folding together sections 16, 14, in that order, and in the direction indicated by the arrows of FIG. 2. Section 10 then may be folded in the direction of the arrows to provide the folded unit illustrated in FIG. 3.

This unit may be carried as a pack by means of straps 80. Also, in view of the segmented webbing, there is defined in the interior of the folded unit a pack cavity which may be used to transport blankets, clothing, or other types of gear.

It is to be understood that the form of my invention herein shown and described is to be taken as a preferred example of the same and that various changes in the shape, size and arrangement of parts may be resorted to without departing from the spirit of my invention or the scope of the subjoined claims.

Having thus described my invention, I claim:

1. A folding stretcher comprising:

- (a) a plurality of laterally spaced pairs of sheet metal sections arranged end to end to form an assembly of laterally spaced, elongated side rails and having substantially the entire length of their upper margins bent inwardly to form flanges,
- (b) the ends of the flanges of each section pair facing one end of the assembly of pairs overlapping the oppositely facing ends of the flanges of the section pair next adjacent in articulated sequence,
- (c) a plurality of U-shaped cross bars disposed between the overlapped ends of the section pairs,
- (d) bolt means extending through aligned laterally ex-

40

45

50

tending openings in and hinging together each overlapped section pair and connecting the ends of a cross bar thereto,

- (e) handle means on the opposite ends of the rail assembly,
  - (f) web means stretched between the rails and spaced above the cross bars, and
  - (g) fastening means fastening the web means to the flanges,
  - (h) the stretcher being adjustable between a folded position wherein the section pairs nest one within the adjacent overlapping one by folding at said bolt means from said one end of the assembly and an unfolded position wherein the section pairs are held rigidly aligned by the overlapping flanges at the respective ends thereof.
2. The folding stretcher of claim 1 wherein at least one of the cross bars comprises a U-shaped metal tube having its ends threaded to receive the bolt means.
3. The folding stretcher of claim 1 wherein at least one of the cross bars comprises a horizontal rod, and two vertical side plates fastened one to each end of the rod and threaded to receive the bolt means.
4. The folding stretcher of claim 1 wherein the fastening means comprise S-hooks each interconnecting an adjacent pair of openings in the web means and in the flanges.
5. The folding stretcher of claim 1 wherein the web means is provided in longitudinally separate sections, one for each side rail section pair and wherein the sheet metal rail sections are of sufficient width to form a pack cavity inside the stretcher when the stretcher is in folded position.
6. The folding stretcher of claim 1 wherein the sides of the section pairs are successively narrower toward said one end of the assembly to maintain the straight line relation of the lower edges thereof.
